[57] CLAIM

The ornamental design for a lawn tractor, as shown and described.

DESCRIPTION

FIG. 1 is a front elevational view of a lawn tractor showing our new design;

FIG. 2 is a rear elevational view thereof;

FIG. 3 is a bottom plan view thereof;

FIG. 4 is a top plan view thereof;

FIG. 5 is a side elevational view taken from the right of FIG. 1;

FIG. 6 is a side elevational view taken from the left of FIG. 1;

FIG. 7 is a left side perspective view thereof;

FIG. 8 is a right side perspective view thereof;

FIG. 9 is a left side perspective view with the chute and grass bag removed for ease of illustration.

FIG. 1
